EDWARD T. FOOTE, OF MONTCLAIR, NEW JERSEY, ASSIGNOR TO THE CUTLER-HAMMER MFG. CO., OF MILWAUKEE, WISCONSIN, A CORPORATION OF WISCONSIN.

CONTROLLING MECHANISM.

1,181,300.

Specification of Letters Patent.

Patented May 2, 1916.

Application filed February 12, 1915. Serial No. 7,837.

To all whom it may concern:

Be it known that I, EDWARD T. FOOTE, a citizen of the United States, residing at Montclair, in the county of Essex and State 5 of New Jersey, have invented new and useful Improvements in Controlling Mechanisms, of which the following is a full, clear, concise, and exact description, reference being had to the accompanying drawing, 10 forming a part of this specification.

This invention relates to controlling mechanisms for electrically propelled ore bridges and the like.

As is understood, ore bridges are commonly propelled by two motors acting independently on opposite ends thereof and in practice it frequently happens, through carelessness of the operator or otherwise, that the bridge becomes skewed on its 20 tracks. Undue skewing in the case of articulated bridges has been overcome by skew limit switches, but the switches used for this type of bridge are inapplicable to the rigid or stiff-legged type.

25 The present invention has among its objects to provide a skew limit switch mechanism suitable for stiff-legged bridges.

Another object of the invention is to provide a limit switch mechanism which will 30 function as desired upon skewing of the bridge but which will be free from interference by any shifting of the bridge not of the skewing character.

A further object is to provide a skew 35 limit mechanism for stiff-legged bridges which may be utilized in various different ways to effect the desired results.

Various other objects and advantages of 40 the invention will hereinafter appear.

The accompanying drawings illustrate 45 one embodiment of the invention and the same will now be described, it being understood that the invention is not limited to the specific embodiment thereof illustrated.

In the drawings, Figure 1 is a schematic 50 view showing in top plan a stiff-legged bridge equipped with driving motors and skew limit switches; Fig. 2 is a detail view of one limit switch; and Fig. 3 is a grammatic view of a simplified controller for the two driving motors exemplifying one use of the limit switches.

Referring to Fig. 1 the bridge is schemati-

cally illustrated as comprising a cross beam 5 provided at opposite ends with stiff or 55 non-articulated legs 6 and 7 having rollers 8 to travel on tracks 9 and 10. The left hand end of the bridge is provided with a propulsion motor 11 operating the left hand rollers 8 through suitable connections 12, 60 while the right hand end of the bridge is provided with a similar propulsion motor 13 driving the right hand rollers 8 through a duplicate set of connections 12. Further, as is schematically illustrated in Fig. 1, the 65 left hand end of the bridge carries two skew limit devices A and B while the right hand end of the bridge carries similar devices C and D.

The limit devices A, B, C and D are all of 70 the same construction and as illustrated in Fig. 2 each comprises two spring closed switches 14 and 15 having arranged therebetween a pivoted member 16 provided with a bifurcated portion 17 to straddle one of 75 the tracks on which the bridge travels. The member 16 normally stands between and out of engagement with both switches but is operable in opposite directions to open said switches selectively and, as will be apparent, 80 bodily movement of the whole device transversely of the track provides for such movements of the member 16. Thus it will likewise be apparent that if the two devices 85 on each leg of the bridge be arranged as illustrated in Fig. 1 the members 16 thereof will be centered so long as the bridge is 90 squared but will be shifted in one direction or the other whenever the bridge is skewed, according to the direction of travel of the 95 bridge and the relation of the ends thereof. For example, if the bridge is traveling in the direction of the arrow and is skewed to advance its right hand end then the members 16 of the devices C and A will be rotated 100 in a counter-clockwise direction to open the switch 14 of each while the members 16 of devices D and B will be rotated in a clockwise direction to open their respective switches 15. On the other hand, with the 105 bridge traveling in the same direction, skewing by advance of the left hand end of the bridge effects just the reverse operations of the limit devices. As will be apparent, similar conditions obtain upon reverse operation of the bridge. Also, lateral shift-

ing of the bridge without skewing will operate the members 16 of the various limit devices, but as will hereinafter be set forth, the devices are functionally dependent upon operation of the several switches in pairs and the switches of each pair are so disposed as to require a skewing action of the bridge in order to operate the same simultaneously. For example, the switch 14 of the device A may be paired with the switch 15 of the device B to function only upon operation of both, and under such conditions it will be apparent that while lateral movement of the bridge may open either one or the other of said switches, according to the direction of its motion, a skewing action of the bridge will be required to open both at the same time. While the several switches 14 and 15 are illustrated as of the single pole type, it will be understood that if desired the same may each be provided with a number of poles and that said switches may also be modified in various other respects.

Referring now to Fig. 3 the limit devices A and B have been illustrated as controlling magnetic switches 18 and 19 in turn controlling the continuity of circuit and direction of operation of the driving motor 11 while the right hand limit devices C and D have been illustrated as controlling magnetic switches 20 and 21 similarly controlling the driving motor 13. In brief, the arrangement is such that the limit devices on opposite ends arrest the operation of their corresponding motor upon skewing of the bridge to advance their respective ends and they so function regardless of the direction of travel of the bridge. Thus when the bridge skews the advanced end thereof is arrested while its opposite end is permitted to continue its movement which, of course, tends to square the bridge for continued travel. Obviously, however, the limit switches might be utilized in other ways.

Referring more specifically to Fig. 3 the same also shows schematically a manual controller 22 for the switches 18 and 19 whereby the operation of the motor 11 may be controlled at will and a similar controller 23 for the switches 20 and 21 and hence for the motor 13. When the controller 22 is operated to energize the switch 18 it completes the circuit of the motor 11 from line L by conductor 24 through the upper contacts of switch 18, by conductors 25 and 26 through the armature A of said motor from left to right, by conductor 27 through the lower contacts of switch 18, by conductor 28 through the motor field winding F, by conductor 29 to line L'. This effects operation of the motor in one direction which, it may be assumed, corresponds to that for operating the bridge in the direction of the arrow, Fig. 1. On the other hand, when

the controller 22 is operated to energize switch 19 the motor circuit extends from line L by conductor 24 through the upper contacts of said switch 19, by conductor 27 through the motor armature from right to left, by conductor 26 through the lower contacts of switch 19, by conductors 30 and 28 through the motor field winding and thence as already traced to line L'. This reverses the operation of the motor. The switches 20 and 21 establish precisely the same circuits for motor 13 so that it is needless to specifically describe the same. The motors are thus capable of independent control and as will be understood, the same may be provided with any desired accelerating and speed regulating means.

The switches 14 and 15 of the various limit devices are illustrated in the same relation as in Fig. 1 and the function of these switches will be readily apparent upon tracing the various control circuits. Considering first the control circuits for switch 18 the same extends from line L by conductor 31 through the controller 22 and through the winding of said switch, by conductor 33 through the switch 15 of limit device A and switch 14 of limit device B in parallel, by conductor 34 to line L'. Next, considering switch 19, the control circuit thereof extends as already traced to controller 22 and thence by conductor 35 through the winding of said switch, by conductor 36 through the switch 15 of device B and switch 14 of device A in parallel to conductor 34 and line L'. Thus deenergization of each of the control switches of motor 11, when the controller is in either running position, is dependent upon joint operation of two diagonally disposed limit switches and the two control switches are governed by oppositely disposed pairs of limit switches. Accordingly, as above described, the two limit devices A and B will act to stop the motor 11 whenever the left hand end of the bridge advances beyond the right hand end during either forward or backward travel of the bridge. The connections of limit devices C and D of the windings of switches 20 and 21 are in all respects similar to the connections just described in connection with switches 18 and 19 and therefore do not require specific description. The control circuit of the winding of switch 20 extends through switch 14 of device C and switch 15 of device D in parallel while the control circuit of switch 21 extends through switch 14 of device D and switch 15 of device C in parallel.

As before stated, various modifications may be made in the control mechanism illustrated and it will therefore be understood that the following claims comprehend all modifications falling within the scope thereof.

What I claim as new and desire to secure by Letters Patent is:

1. The combination with a rigid traveling device having power driving means and a definite path of travel, of power controlling means therefor including means associated with said device and operable by skewing movement thereof.
2. The combination with a rigid traveling device, having power driving means and a definite path of travel, of power controlling means therefor including means associated with said device and selectively operable by different skewing movements thereof.
3. The combination with a rigid traveling device having power driving means and a definite path of travel, of automatic power controlling means therefor including skew detecting means associated with and operable by said device.
4. In combination, a rigid traveling device having power driving means and a definite path of travel, of power controlling means therefor including means associated with and operable by said device upon angular movement thereof with respect to its path of travel, said controlling means being functionally independent of angular movement of said device other than of a skewing character.
5. In combination, a traveling bridge or the like, a track therefor and a controlling device for said bridge carried thereby and engaging said track to be operated by skewing movement of said bridge relative to said track.
6. In combination, a traveling bridge, a track therefor and a controlling device for said bridge carried thereby and engaging said track to be operated by skewing movement of said bridge relative to said track and in different ways varying with direction of the skewing movement of said bridge.
7. In combination, a rigid traveling bridge, a track therefor and control means for said bridge including devices fixed to and other devices movably supported on said bridge and the movably supported devices engaging said track to coöperate with said fixed devices upon skewing of said bridge relative to said track.
8. In combination, a rigid traveling bridge, a track therefor and a controlling mechanism for said bridge, including a plurality of devices fixed to said bridge and a device movably supported on said bridge

and engaging said track to coöperate with said former devices selectively upon skewing movements of said bridge.

9. In combination, a traveling device having a definite path of travel, a plurality of controlling devices therefor, operable upon skewing movement of said traveling device or lateral play thereof but so associated as to be functionally unresponsive except upon skewing movement of said traveling device.

10. In combination, a rigid traveling device having a definite path of travel and a plurality of control devices therefor operable by movement of said device out of its path of travel and in different combinations according to the angular position of said traveling device with respect to its path of travel.

11. In combination, a rigid traveling device having a definite path of travel, and a plurality of control devices therefor responsive to movements of said device out of said path but each being functionally dependent upon operation of another.

12. In combination, a rigid traveling device having a definite path of travel and a plurality of controlling devices therefor operable selectively by said device upon movements thereof out of said path, each of said controlling devices being functionally dependent upon another.

13. In combination, a rigid traveling device having a definite path of travel and a plurality of controlling devices therefor operable selectively by said device upon movements thereof out of said path, each of said controlling devices being functionally dependent upon another to function only upon skewing movements of said traveling device.

14. In combination, a traveling device having a definite path of travel, a plurality of controlling devices therefor operable selectively by movements of said traveling device out of said path of travel, said devices coöoperating in groups and the devices of each group being responsive for coöperation only upon skewing movements of said traveling device.

In witness whereof, I have hereunto subscribed my name in the presence of two witnesses.

EDWARD T. FOOTE.
